(57) **CLAIM**

The ornamental design for a soft side cooler with utility board, as shown and described.

DESCRIPTION

FIG. 1 is a perspective front view of the soft side cooler with utility board.

FIG. 2 is a front view thereof.

FIG. 3 is a rear view thereof.

FIG. 4 is a left side view thereof.

FIG. 5. is a right side view thereof; and,

FIG. 6 is a top view thereof.

The bottom of the soft side cooler with utility board not shown in the drawings is plain and devoid of markings.

The broken lines in the drawings are shown for environmental purpose only and are not part of the claimed design.

1 Claim, 6 Drawing Sheets
